UNITED STATES PATENT OFFICE.

WILLIAM McCALLUM, OF YONKERS, N. Y., ASSIGNOR TO THE BIGELOW CARPET COMPANY, OF CLINTON, MASS.

DESIGN FOR CARPETS.

SPECIFICATION forming part of Design No. 12,193, dated March 22, 1881.

Application filed February 19, 1881. Term of patent 34 years.

To all whom it may concern:

Be it known that I, WILLIAM McCALLUM, of Yonkers, in the county of Westchester and State of New York, have invented a new and original Design for Carpets, of which the following is a specification.

This invention relates to a new and original design for carpets and similar fabrics; and it consists of the novel grouping and configuration of figures, hereinafter more fully described.

The accompanying photograph illustrates a face view of a carpet having my new design.

A is a vine-like figure running across the design, and bearing upon it leaves, flowers, and flowering branches and shoots. From this vine A projects the figure O, consisting of a cluster of flowers and leaves; also, the figure e, a projecting branch of the vine A, bearing on it circular flowers and leaves; also, the figure b, forming another branch of the vine A, and bearing upon it leaves and circular flowers similar to those of the branch e, and terminating in a projecting willow-like branch, from which grow pendent bell-shaped flowers. The other end of the vine A is formed by the projecting branch a, bearing on it leaves and circular flowers similar to those of the figures b and e.

30 B is a figure resembling a bush, bearing

upon it leaves and fully-opened circular flowers near its center, around which project flower-sprays and leaves.

The interstices between the figures described are filled by a regular-patterned background, 35 formed by the repetition, in regular order, of the small figures of peculiar shape shown in the photograph, and the whole effect of the design is that of the branching vine and the flowering bush described resting upon this 40 regular background, which appears in the interstices between the figures.

I claim—

1. The design for carpets, consisting of the figure b, substantially as shown. 45
2. The design for carpets, consisting of the figure a, substantially as shown.
3. The design for carpets, consisting of the figure e, substantially as shown.
4. The design for carpets, consisting of the figures A a b e o, substantially as shown. 50
5. The design for carpets, consisting of the figure B, substantially as shown.
6. The design for carpets, consisting of the figures A e b a o B and patterned background, 55 substantially as shown.

WILLIAM McCALLUM.
